ABSTRACT OF THE DISCLOSURE

The invention provides a naphthyridine derivative of 15 formula:

wherein R₁ is lower alkyl of 1 to 3 carbon atoms, R₂ is hydrogen or methyl, each of the two symbols R₃ is lower alkoxy of 1 to 4 carbon atoms, or together the two symbols R₃ are methylenedioxy, and each of the two symbols X is hydrogen, or together the two symbols X are a second bond between the carbon and the nitrogen atom, and a pharmaceutically acceptable acid addition salt thereof.

The compounds and their pharmaceutically acceptable salts are indicated for use in medicaments, especially in the treatment of pains of various origins.

The present invention relates to new heterocyclic compounds and processes for their production.

The present invention provides naphthyridine derivatives of Formula I,

(I) 55

in which:

R₁ signifies a lower alkyl radical of 1-3 carbon atoms, R₂ signifies a hydrogen atom or a methyl radical, each of the two symbols

R₃ signifies a lower alkoxy radical of 1-4 carbon atoms, or together the two symbols

R₃ signifies methylenedioxy, and each of the two symbols X signifies a hydrogen atom, or together the two symbols X signifies a second bond between the carbon and the nitrogen atom,

and their acid addition salts.

The new compounds have a benzo[c][1,6]naphthyridine structure, the numbering of which may be seen in 70 Formula I. There is a cis ring linkage in the positions 4a and 10b.

2

The present invention further provides processes for the production of compounds I and their acid addition salts, characterized in that

(a) A compound of Formula Ia,

(Ia)

in which R₁, R₂ and the two symbols R₃ have the above significance, is produced by cyclizing a compound of Formula II,

(II)

in which R₁, R₂ and the two symbols R₃ have the above significance, by treating with an acid water-removing condensation agent; or

(b) A compound of Formula Ib,

(Ib)

in which R₁, R₂ and the two symbols R₃ have the above significance, is produced by reducing the double bond in the 5-6 position of the above compound of Formula Ia; or

(c) A compound of the above Formula Ib is produced by reacting, under acid conditions, a piperidylamine of Formula III,

(III)

in which R₁ and the two symbols R₃ have the above significance, with an aldehyde of Formula R₂—CHO, or with a reactive functional derivative thereof, in which R₂ has the above significance; and where an acid addition salt is required, salification is effected.

Any mixtures of isomers which may result may subsequently be separated into their individual racemates or epimeric forms, and any individual racemates which result may be separated into their optically active components.

The amides of Formula II used as starting materials have hitherto not been described in the literature, and form part of the present invention. They may be obtained by formylation or acetylation of piperidylamines of Formula III.

Formylation may be effected by heating the piperidylamines of Formula III with formamide, formic acid or a lower alkyl ester of formic acid, or by reacting at room temperature with a mixture of formic acid and acetic anhydride. For example, *cis*-3-(3,4-dimethoxyphenyl)-1-methyl-4-piperidylamine is heated to 100-130° C. for 4 hours in an atmosphere of nitrogen with an excess of formamide, the cooled reaction mixture is diluted with water and extraction is effected several times with a water-immiscible organic solvent, e.g. chloroform; the combined organic phases are subsequently washed with a saturated aqueous sodium chloride solution, are dried, e.g. over sodium sulphate, and concentrated by evaporation, whereby crude *cis*-3-(3,4-dimethoxyphenyl)-4-formylamino-1-methylpiperidine is obtained as residue.

The acetylation of the piperidylamines of Formula III is preferably effected by reacting with acetic anhydride or acetyl chloride. In this reaction, the presence of an acid-binding agent, e.g. a tertiary organic base such as pyridine, is advantageous but not essential. A small excess, e.g. 1.2 to 2 mols, of acetic anhydride is added, for example, to *cis*-3-(3,4-dimethoxyphenyl)-1-methyl-4-piperidylamine in an organic solvent which is inert under the reaction conditions, e.g. chloroform, the mixture is stirred for 1 to 3 hours at room temperature, is subsequently heated to the boil under reflux for a short time, e.g. half an hour, and the resulting *cis*-4-acetylamino-3-(3,4-dimethoxyphenyl)-1-methylpiperidine is isolated by the addition of water and an alkali, e.g. potassium carbonate, and subsequent extraction with a water-immiscible organic solvent, e.g. chloroform.

The amides of Formula II have *cis* substituents in the positions 3 and 4 of the piperidine ring, as do the piperidylamines of Formula III, and may be obtained as *cis* racemates or as optically uniform *cis* compounds. A splitting of the *cis* racemates into their optical antipodes is possible in the amide and in the amine stage. The piperidylamines of Formula III are preferably used as *cis* racemates, whereby the amides of Formula II are also obtained as *cis* racemates. The ring closure reaction, which is effected in accordance with the known method of Bischler and Napieralski, does not alter the steric arrangement of the substituents on the piperidine ring, so that the stereochemistry in the positions 4a and 10b (ring linkage) of the resulting 1,2,3,4,4a,10b-hexahydrobenzo[c][1,6]naphthyridine derivatives of Formula Ia corresponds to that of the starting materials. *Cis* racemates or optically uniform *cis* compounds are thus obtained, depending on the composition of the starting materials.

Cyclization is effected by heating the amides of Formula II to the boil under reflux with phosphorus oxychloride and/or phosphorus pentoxide in an organic solvent which is inert under the reaction conditions, e.g. chloroform, benzene, toluene, xylene or tetraline, for some time, e.g. 3 to 10 hours. In accordance with another embodiment of the process, the ring closure is effected in an excess of boiling phosphorus oxychloride or in a mixture of phosphorus pentoxide and boiling phosphorus oxychloride.

For example, *cis*-3-(3,4-dimethoxyphenyl)-4-formylamino-1-methylpiperidine is heated to the boil under reflux with an excess of phosphorus oxychloride in chloroform for about 1 hour, the liquid is decanted from the resulting precipitate after cooling the reaction mixture, the residue is taken up in water, and the resulting solution is heated on a boiling water bath for some time, e.g. 15 minutes; the resulting 8,9-dimethoxy-1,2,3,4,4a,10b-hexahydro-2-methylbenzo[c][1,6]naphthyridine may be liberated from the solution with an alkali, e.g. by the addition of solid potassium carbonate.

Other reagents which are suitable for the cyclization of the invention in accordance with Bischler-Napieralski, preferably polyphosphoric acid, phosphorus pentachloride, aluminium chloride or zinc chloride, may likewise be used as condensation agents in place of phosphorus oxychloride and/or phosphorus pentoxide.

The 1,2,3,4,4a,10b-hexahydrobenzo[c][1,6]naphthyridine derivatives obtained as cyclization products in accordance with the process described above have the Formula Ia; if desired, they may be reduced to the corresponding 1,2,3,4,4a,5,6,10b-octahydrobenzo[c][1,6]naphthyridine derivatives. This reduction may be effected by catalytic hydrogenation, e.g. in the presence of platinum, palladium or Raney nickel, in a lower alkanol, e.g. ethanol, at room temperature and at normal pressure or at an elevated pressure. The hexahydrobenzo[c][1,6]naphthyridine derivatives to be reduced may be used as free bases or in the form of their salts, e.g. hydrochlorides. Working up is effected by filtering off the catalyst, evaporating the filtrate to dryness and purifying the crude octahydro compounds obtained as residue in manner known per se.

In accordance with another embodiment of the process a complex alkali metal hydride, e.g. sodium borohydride in methanol or lithium aluminium hydride in ether, tetrahydrofuran, dioxane or dimethoxyethane, is used as reducing agent. In this case, after decomposing the excess reducing agent and the resulting complex by shaking out with water and a water-immiscible organic solvent, e.g. benzene, the reduction products are isolated and subsequently purified in manner known per se.

Nascent hydrogen may also be used for reduction, in which case the hexahydrobenzo[c][1,6]naphthyridine derivative is treated, for example, with metallic zinc or tin in an aqueous acid, with metallic sodium in a lower alkanol or with sodium amalgam in water.

When R_2 in the 1,2,3,4,4a,10b-hexahydrobenzo[c][1,6]naphthyridine derivatives of Formula Ia used signifies the methyl radical, a center of asymmetry is formed in the 6-position of the ring structure upon reduction, so that the resulting 6-methyl-1,2,3,4,4a,5,6,10b-octahydrobenzo[c][1,6]naphthyridine derivatives may be obtained in two racemates or in two (optically active) epimeric forms. The reduction of the double bond in the position 5-6, however, mostly occurs stereospecifically and therefore usually only yields one of the two possible racemates (or epimers), or a mixture, in which one of the two racemates (or epimers) predominates.

1,2,3,4,4a,5,6,10b-octahydrobenzo[c][1,6]naphthyridine derivatives of Formula Ib may also be produced in accordance with the known method of Pictet and Spengler. A piperidylamine of Formula III is reacted with formaldehyde or acetaldehyde or with a reactive functional derivative of these aldehydes, e.g. methylal, under acid conditions, whereby the steric arrangement of the substituents on the piperidine ring is not altered, as is the case in the ring closure in accordance with Bischler-Napieralski described in section (a), so that the stereochemistry in the position 4a and 10b (ring linkage) of the resulting octahydrobenzo[c][1,6]naphthyridine derivatives of Formula Ib corresponds to that of the starting materials III; the compounds III are preferably used as *cis* racemates. When the ring closure is effected with acetaldehyde, compounds of Formula Ib are obtained, in which R_2 signifies methyl, and which have a center of asymmetry in the 6 position of the ring structure and therefore may be obtained in two racemates or two (optically active) epimers. A mixture of isomers is usually obtained, in which one of the two racemates (or epimers) predominates.

The amine of Formula III is heated, for example, with an excess (10 to 100%) of acetaldehyde or formaldehyde, e.g. with an aqueous formaldehyde solution, to 100° C. for 15 to 60 minutes. An excess (about 1.1 mols) of hydrochloric acid, of an aqueous hydrogen bromide solution

or dilute sulphuric acid, is added to the reaction mixture and heating to the boil under reflux is subsequently effected for 15 minutes to 8 hours. The resulting octahydrobenzo[c][1,6]naphthyridine derivatives of Formula Ib may be isolated in the form of their salts or may be liberated from the reaction solution with an alkali, e.g. by the addition of an aqueous potassium carbonate solution.

In accordance with another embodiment of the process the piperidylamine of Formula III, as free base or in the form of a salt, e.g. the hydrochloride, is heated to about 100° with formaldehyde or acetaldehyde and an acid, e.g. dilute hydrochloric acid, for 1 to 3 hours. The isolation of the resulting 1,2,3,4,4a,5,6,10b-octahydrobenzo[c][1,6]naphthyridine derivatives of Formula Ib is effected as described above.

As has already been indicated above, 1,2,3,4,4a,5,6,10b-octahydrobenzo[c][1,6]naphthyridine derivatives having a methyl radical in the 6 position may be obtained as mixtures of two racemates or of two (optically active) epimers, in accordance with process (a) and in accordance with process (b). These mixtures may optionally be separated in known manner, e.g. by chromatography or fractional crystallization.

Any individual racemate which may result may optionally be separated into its optically active components. For this purpose the racemate is treated with an optically active acid, e.g. d-tartaric acid, 1-malic acid, d- or L-mandelic acid, the resulting diastereoisomeric salts are separated by fractional crystallization and the bases are optionally liberated from the resulting optically uniform salts with an alkali.

The final products of Formula I, as mixtures of racemates or epimers, as sterically uniform racemates or as pure optically active compounds, may subsequently be converted with inorganic or organic acids into the corresponding salts. Examples of acids for acid addition formation are hydrochloric, hydrobromic, sulphuric, maleic, fumaric, malic, tartaric, benzoic, methanesulphonic, p-toluenesulphonic and cyclohexylsulphamic acid.

Piperidylamines of Formula III may, for example, be produced as follows:

A phenylacetic acid of Formula IV,

in which the two R₃ have the above significance, is converted into its lower alkyl ester, e.g. with an excess of the corresponding lower alkanol in the presence of an acid, e.g. hydrochloric acid. The resulting ester is reacted in the presence of a strong basic condensation agent, e.g. sodium ethylate in toluene, with a lower dialkyl ester of oxalic acid. The resulting compound of Formula V,

in which the two R₃ have the above significance, and each of R₄ and R₅ signifies lower alkyl, is treated with formaldehyde, e.g. with an aqueous formaline solution, in the presence of an alkali, e.g. potassium carbonate, and the reaction product is distilled, whereby a phenylacrylic acid ester of Formula VI,

in which the two R₃ and R₄ have the above significance, is obtained.

The phenylacrylic acid ester of Formula VI is condensed with an amine of formula R₁-NH₂, in which R₁

has the above significance, and the condensation product is reacted with a compound of Formula VII,

in which Y signifies chlorine or bromine, and R₆ signifies lower alkyl, in the presence of an acid-binding agent, whereby a compound of Formula VIII,

in which R₁, the two R₃, R₄ and R₆ have the above significance, is obtained. Compounds of Formula VIII may also be obtained by reacting a phenylacrylic acid ester of the above Formula VI with an amino acid ester of Formula IX,

in which R₁ and R₆ have the above significance.

The compounds of Formula VIII are cyclized by heating with a strong basic condensation agent, e.g. sodium hydride in toluene; the resulting products are converted by hydrolysis and decarboxylation into the corresponding piperidones of Formula X,

in which R₁ and the two R₃ have the above significance, e.g. by heating in an aqueous mineral acid, for example 3-6 N hydrochloric acid.

The piperidones of Formula X are reacted with hydroxylamine hydrochloride and the resulting oximes are reduced to the corresponding piperidylamines, e.g. by hydrogenation over a metal catalyst, e.g. Raney nickel, by reaction with complex alkali metal hydrides, e.g. lithium aluminium hydride or sodium borohydride, or with metallic sodium in a lower alkanol. In accordance with another embodiment of the process the piperidones X are hydrogenated catalytically in the presence of ammonia, e.g. in an ethanolic ammonia solution in the presence of Raney nickel at an elevated temperature and under pressure, whereby the imines resulting as intermediates are reduced in situ to the corresponding piperidylamines. The above-indicated reductions generally yield mixtures of the two possible racemates, the composition in percentages of which may vary depending on the reduction conditions. The cis-piperidylamines of Formula III are separated from these mixtures as racemates in manner known per se, e.g. by fractional crystallization of their acid addition salts or by adsorption chromatography; the resulting cis racemates are optionally separated into their optically active components in manner known per se.

The compounds of Formula I and their acid addition salts have hitherto not been described in the literature. These compounds and their pharmaceutically acceptable salts exhibit therapeutically useful pharmacodynamic properties. Thus, for instance, in the well known hot-plate test carried out with mice, the compounds are shown to exhibit pronounced analgesic effects. For example, the compound 8,9 - dimethoxy-2-methyl-1,2,3,4,4a,5,6,10b-octahydrobenzo[c][1,6]-naphthyridine, such as in the form of its bis-(hydrogen maleinate), administered p.o., is particularly effective in this test. Compounds of Formula I and their pharmaceutically acceptable salts are therefore indicated for use in medicaments, especially in the treatment of pains of various origins. A suitable

average daily dose amounts to from 1 to 10 mg./kg. body weight of warm-blooded animals, such as primates.

The compounds of Formula I and their pharmaceutically acceptable acid addition salts are of a low toxicity. The compounds I and their pharmaceutically acceptable salts may thus be administered at the daily dosages indicated.

The compounds of the invention or their water-soluble physiologically tolerated acid addition salts may be used as pharmaceuticals on their own or in the form of appropriate medicinal preparations, e.g. tablets, dragees, suppositories, injectable solutions, for administration, e.g. enterally or parenterally. Aside from the usual inorganic or organic, pharmacologically inert adjuvants, e.g. lactose, starch, talcum, stearic acid, water, alcohols, glycerin, natural or hardened oils or waxes, these preparations may also contain suitable preserving, stabilizing or wetting agents, solubilizers, sweetening or colouring substances and flavourings.

The term "in manner known per se" as used herein designates methods in use or described in the literature on the subject.

In the following non-limitative examples all temperatures are indicated in degrees centigrade, without corrections.

EXAMPLE 1

8,9-dimethoxy-2,6-dimethyl-1,2,3,4,4a,10b-hexahydrobenzo[c][1,6]naphthyridine

120 g. of phosphorus oxychloride are added to a solution of 153 g. of cis-4-acetylamino-3-(3,4-dimethoxyphenyl)-1-methylpiperidine (racemate) in 500 cc. of benzene during the course of 10 minutes while stirring and cooling with ice. The mixture is stirred at room temperature for half an hour and is subsequently heated to the boil at reflux for 2½ hours, whereby an oil precipitates, which gradually crystallizes. The excess phosphorus oxychloride and the benzene are subsequently removed by distillation at reduced pressure, 500 cc. of water are carefully added to the resulting residue and heating is effected on a boiling water bath for half an hour. 200 g. of solid potassium carbonate are added to the resulting brown solution, and the oil which precipitates is extracted with chloroform. The chloroform layer is washed with a saturated aqueous sodium chloride solution, is dried over sodium sulphate and concentrated by evaporation. The resulting residue is subsequently taken up in 200 cc. of ethanol, 520 cc. of a 2 N solution of hydrogen chloride in ethanol are added, 400 cc. of ether are added and the mixture is allowed to stand in a refrigerator for 16 hours, whereby the dihydrochloride of the compound indicated in the heading (racemate) precipitates in the form of slightly hygroscopic crystals; M.P. 218° (decomp.) after drying in a high vacuum for 16 hours at 70°; contains 0.5 to 1 mol of water of crystallization. The base obtained from the dihydrochloride by liberating with potassium carbonate is recrystallized from ethyl acetate; M.P. 125°.

The starting material may be produced as follows:

(a) 2-(3,4-dimethoxyphenyl)acrylic acid ethyl ester
(3,4-dimethoxyatropic acid ethyl ester)

1435 g. of oxalic acid diethyl ester are added while stirring during the course of 15 minutes to a suspension of sodium ethylate in 3000 cc. of toluene (produced from 113 g. of metallic sodium). 1000 g. of 2-(3,4-dimethoxyphenyl)acetic acid ethyl ester (homoveratric acid ethyl ester) are added to the resulting solution at a temperature of 30-40° during the course of 25 minutes, and a resulting dark solution is heated to the boil at reflux while stirring for 2 hours. Cooling is subsequently effected to -45°, 1230 cc. of 4 N sulphuric acid are subsequently allowed to flow in at a temperature of -10° during the course of 3 hours and 0.5 g. of hydroquinone are subsequently added.

400 g. of a formaline solution (36% formaldehyde in water) are allowed to flow into the above reaction mixture, and 120 cc. of a saturated aqueous potassium carbonate solution are subsequently added dropwise during the course of 1 hour. The mixture is stirred at room temperature for 2½ hours and a further 200 g. of formaline solution are subsequently added. The reaction mixture is stirred at room temperature over night and is subsequently diluted with 4000 cc. of water. The toluene layer is separated, washed once with water, dried over sodium sulphate and concentrated by evaporation in a vacuum after the addition of 0.5 g. of hydroquinone. The residue is distilled in a high vacuum, whereby decomposition initially occurs; the relatively unstable 2-(3,4-dimethoxyphenyl)acrylic acid ethyl ester distills over at 135-140°/0.06 mm. of Hg as a yellow viscous oil and is further worked up without delay.

(b) 5-ethoxycarbonyl-3-(3,4-dimethoxyphenyl)-1-methyl-4-piperidone

412 g. of 3-methylaminopropionic acid ethyl ester are added during the course of 30 minutes while stirring to 738 g. of above 2-(3,4-dimethoxyphenyl)acrylic acid ethyl ester, and the mixture is stirred at room temperature for 72 hours.

2500 cc. of toluene are subsequently added to 300 g. of a sodium hydride suspension (50% in paraffin oil), and 150 g. of the above reaction mixture are allowed to flow in in an atmosphere of nitrogen. Heating is effected to 80°, and after the reaction commences, the remaining 1000 g. of the above reaction mixture are added dropwise during the course of 2 hours. The mixture is subsequently heated to the boil at reflux for 4 hours, is cooled to -10°, 376 cc. of glacial acetic acid are carefully added and 340 cc. of water are allowed to flow in while stirring well; a crystalline precipitate gradually results, which is separated by filtration. Most of the toluene is removed from the filtrate in a vacuum, and a solution of hydrogen chloride in ethanol is added while stirring and cooling well until an acid reaction to Congo red is obtained. 2500 cc. of ether are added, the mixture is allowed to stand over night in a refrigerator, and the resulting precipitate is filtered off. The resulting 5-ethoxycarbonyl-3-(3,4-dimethoxyphenyl)-1-methyl-4-piperidone hydrochloride has a M.P. of 190-192° (decomp.).

(c) 3-(3,4-dimethoxyphenyl)-1-methyl-4-piperidone

50 1170 g. of 5-ethoxycarbonyl-3-(3,4-dimethoxyphenyl)-1-methyl-4-piperidone hydrochloride are heated to the boil at reflux for 2½ to 3 hours in 5000 cc. of 4 N hydrochloric acid. The hydrochloric acid is evaporated in a vacuum, 755 cc. of water are added, 3-(3,4-dimethoxyphenyl)-1-methyl-4-piperidone is precipitated in the form of an oil by the addition of a large amount of potassium carbonate, and extraction is effected with 2500 cc. of chloroform. The chloroform solution is dried over sodium sulphate and concentrated by evaporation, whereby the compound indicated in the heading is obtained as residue; the picrate has an M.P. of 191-192° (decomp.) after crystallization from ethanol.

(d) 3-(3,4-dimethoxyphenyl)-1-methyl-4-piperidone-oxime

65 The crude 3-(3,4-dimethoxyphenyl)-1-methyl-4-piperidone obtained in section (c) is taken up in 800 cc. of ethanol and a suspension of 250 g. of hydroxylamine hydrochloride in 2300 cc. of hot ethanol is added while stirring. The mixture is heated to the boil at reflux for 4 hours, the crystalline mash is subsequently stirred at room temperature for a further 12 hours and filtration is effected. The resulting crude 3-(3,4-dimethoxyphenyl)-1-methyl-4-piperidone-oxime hydrochloride has a M.P. of 220-221° (decomp.). The free base as an M.P. of 150° after crystallization from ethanol.

(e) 3-(3,4-dimethoxyphenyl)-1-methyl-4-piperidylamine

350 g. of 3-(3,4-dimethoxyphenyl)-1-methyl-4-piperidone-oxime are hydrogenated in 2500 cc. of ethanol over Raney nickel in an autoclave for 6 hours at 80° and 51 atmospheres. After cooling the catalyst is filtered off, the filtrate is concentrated to a volume of 500 cc. and 760 cc. of a 3.53 N solution of hydrogen chloride in ethanol is added; the colourless precipitate is filtered off after cooling the solution to 35°. This precipitate is the practically pure dihydrochloride of the cis isomer (racemate) of the compound indicated in the heading; M.P. 321° (decomp.) after crystallization from 80% ethanol. Free base: B.P. 135°/0.04 mm. of Hg, M.P. 78-80° (from ethyl acetate/petroleum ether). The dihydrochloride of the corresponding trans isomer (racemate) remains in the filtrate and then also crystallizes; M.P. 280° (decomp.) after crystallization from 90% ethanol.

(f) cis-4-acetylaminino-3-(3,4-dimethoxyphenyl)-1-methylpiperidine

102 g. of acetic anhydride are added during the course of 45 minutes while stirring and cooling with ice to 125 g. of cis-3-(3,4-dimethoxyphenyl)-1-methyl-4-piperidylamine (racemate), dissolved in 250 cc. of chloroform. Stirring is effected at room temperature for 2 hours and the reaction solution is subsequently heated to the boil at reflux for half an hour. Cooling is effected, 250 cc. of a saturated aqueous potassium carbonate solution are added while cooling and solid potassium carbonate is added to the solution, whereby an oily product precipitates, which is extracted with chloroform. The chloroform layer is separated, washed with a saturated aqueous sodium chloride solution, dried over sodium sulphate and concentrated by evaporation. The cis-4-acetylaminino-3-(3,4-dimethoxyphenyl)-1-methylpiperidine (racemate) is obtained in the form of a hard, glassy residue, which is further worked up as crude product without purification.

EXAMPLE 2

8,9-dimethoxy-2,6-dimethyl-1,2,3,4,4a,5,6,10b-octahydrobenzo[c][1,6]naphthyridine

20.0 g. of 8,9-dimethoxy-2,6-dimethyl-1,2,3,4,4a,10b-hexahydrobenzo[c][1,6]naphthyridine (racemate, production see Example 1) are dissolved in 250 cc. of ethanol and shaken with hydrogen over 0.5 g. of a platinum catalyst at normal pressure and room temperature. After the calculated molar amount of hydrogen has been taken up, the catalyst is filtered off, the filtrate is concentrated by evaporation, 80 cc. of a 2 N solution of hydrogen chloride in ethanol are added to the oil obtained as residue, 150 cc. of ether are subsequently added and the mixture is allowed to stand in a refrigerator for 16 hours. The dihydrochloride of the compound indicated in the heading (racemate) which crystallizes is filtered off and recrystallized from 98% methanol and a small amount of ether; M.P. 328° (decomp.). The base liberated therefrom with potassium carbonate has an M.P. of 122° (after crystallization from ether); mixed M.P. with 8,9-dimethoxy-2,6-dimethyl-1,2,3,4,4a,10b-hexahydrobenzo[c][1,6]naphthyridine 95-110°.

EXAMPLE 3

2,6-dimethyl-1,2,3,4,4a,10b-hexahydro-8,9-methylenedioxybenzo[c][1,6]naphthyridine

2.6 g. of cis-4-acetylaminino-1-methyl-3-(3,4-methylenedioxyphenyl)piperidine (racemate) are dissolved in 50 cc. of absolute benzene and 3.0 g. of phosphorus oxychloride are added. The mixture is heated to the boil reflux for 4 hours and the benzene and excess phosphorus oxychloride are subsequently evaporated. 25 cc. of water are added to the resulting residue, heating is effected on a boiling water bath for 40 minutes, solid potassium carbonate is added to the resulting clear, yellow solution while cooling with ice until an alkaline reaction is

obtained, and extraction is effected thrice with chloroform. The combined chloroform layers are washed with a saturated aqueous sodium chloride solution, dried over sodium sulphate and concentrated by evaporation. The 2,6-dimethyl-1,2,3,4,4a,10b-hexahydro-8,9-methylenedioxybenzo[c][1,6]naphthyridine (racemate) obtained as residue is converted into its dihydrochloride by the addition of 10 cc. of a 3 N solution of hydrogen chloride in ethanol; M.P. 299° (decomp.).

10 The starting material may, for example, be produced as follows:

(a) 2-(3,4-methylenedioxyphenyl)acetic acid ethyl ester

15 A suspension of 100 g. of 2-(3,4-methylenedioxyphenyl)acetic acid in 300 cc. of absolute ethanol is saturated with dry hydrogen chloride gas while stirring, whereby the material gradually dissolves. The solution is allowed to stand at room temperature for 36 hours, the excess ethanol is subsequently evaporated and the yellow, oily residue is taken up in ether. The resulting ether solution is shaken out with ice water, then with an aqueous sodium hydrogen carbonate solution and again with ice water, is dried over sodium sulphate and concentrated by evaporation. The residue is distilled in a high vacuum; the compound indicated in the heading has a B.P. of 100°/0.01 mm. of Hg.

(b) 2-(3,4-methylenedioxyphenyl)acrylic acid ethyl ester

20 170 g. of oxalic acid diethyl ester are added while stirring during the course of 5 minutes to a suspension of sodium ethylate in 300 cc. of absolute toluene (produced from 13.4 g. of metallic sodium), whereby the material dissolves. 110 g. of 2-(3,4-methylenedioxyphenyl)-acetic acid ethyl ester are then added at a temperature of 30-40° and the resulting dark solution is heated to the boil at reflux while stirring for 2 hours. Cooling is subsequently effected to -45° and 146 cc. of 4 N aqueous sulphuric acid are allowed to flow in at a temperature of -10° during the course of 3 minutes; subsequently

25 0.1 g. of hydroquinone is added.

30 49 g. of a formaline solution (36% formaldehyde in water) are allowed to flow into the above reaction mixture while stirring, and 155 cc. of a saturated aqueous potassium carbonate solution are subsequently added dropwise during the course of 15 minutes. The mixture is stirred at room temperature for 2½ hours and a further 30 g. of formaline solution are added. The reaction mixture is stirred at room temperature over night and is then diluted with 500 cc. of water. The toluene layer is separated, washed once with water, dried over sodium sulphate and concentrated in a vacuum after the addition of 0.5 g. of hydroquinone. The residue is distilled in a high vacuum, whereby decomposition initially occurs; the relatively unstable 2-(3,4-methylenedioxyphenyl)acrylic acid ethyl ester distils over at 114°/0.02 mm. of Hg as a yellow, viscous oil and is further worked up without delay.

(c) 5-ethoxycarbonyl-1-methyl-3-(3,4-methylenedioxyphenyl)-4-piperidone

35 53 g. of 3-methylaminopropionic acid ethyl ester are added within the course of 10 minutes while stirring to 88 g. of the above 2-(3,4-methylenedioxyphenyl)acrylic acid ethyl ester and the mixture is stirred at room temperature for 72 hours.

40 400 cc. of absolute toluene are then added to 38.4 g. of a sodium hydride suspension (50% in paraffin oil) and 20 g. of the above reaction mixture are allowed to flow in in an atmosphere of nitrogen. Heating is effected to 80° and after the reaction commences the remaining 121 g. of the above reaction mixture are added dropwise during the course of 1 hour. Heating to the boil at reflux is subsequently effected for 4 hours, cooling is effected to -10° and 48 g. of glacial acetic acid and 44 cc. of water are carefully added; a crystalline precipitate gradually re-

sults, which is separated by filtration. Most of the toluene is removed from the filtrate in a vacuum and a solution of hydrogen chloride in ethanol added while stirring and cooling well until an acid reaction to Congo red is obtained, whereupon crystallization commences. 200 cc. of ether are added, the mixture is allowed to stand in a refrigerator over night and is filtered. The resulting 5-ethoxycarbonyl - 1 - methyl - 3 - (3,4 - methylenedioxyphenyl)-4-piperidone hydrochloride has a M.P. of 212° (decomp.) (after crystallization from methanol/ether).

(d) 1-methyl-3-(3,4-methylenedioxyphenyl)-4-piperidone

65 g. of 5-ethoxycarbonyl-1-methyl-3-(3,4-methylenedioxyphenyl)-4-piperidone hydrochloride are heated to the boil at reflux for 2½ to 3 hours in 500 cc. of 4 N hydrochloric acid. The hydrochloric acid is evaporated in a vacuum, 100 cc. of water are added to the residue, 1-methyl-3-(3,4-methylenedioxyphenyl)-4-piperidone is precipitated in the form of an oil by the addition of a large amount of potassium carbonate and extraction is effected with 300 cc. of chloroform. The chloroform solution is dried over sodium sulphate and concentrated by evaporation; the compound indicated in the heading is obtained as residue and is directly worked up as crude product.

(e) 1-methyl-3-(3,4-methylenedioxyphenyl)-4-piperidone-oxime

The crude 1-methyl-3-(3,4-methylenedioxyphenyl)-4-piperidone obtained above is taken up in 70 cc. of ethanol and a suspension of 12.5 g. of hydroxylamine hydrochloride in 10 cc. of hot ethanol is added while stirring. The mixture is heated to the boil at reflux while stirring for 4 hours and the crystalline mash is subsequently stirred at room temperature for a further 12 hours. Evaporation to dryness is effected, the residue is taken up in 75 cc. of water, the oxime is precipitated by the addition of a saturated aqueous potassium carbonate solution and extraction is effected with chloroform. The chloroform layer is separated, dried over sodium sulphate and concentrated by evaporation; the compound indicated in the heading is obtained as a viscous oil which crystallizes and which has a M.P. of 153-155° after crystallization from ethyl acetate.

(f) 1-methyl-3-(3,4-methylenedioxyphenyl)-4-piperidylamine

25 g. of 1-methyl-3-(3,4-methylenedioxyphenyl)-4-piperidone-oxime are hydrogenated in 300 cc. of ethanol over Raney nickel in an autoclave at 80° and 51 atmospheres for 6 hours. After cooling, the catalyst is filtered off, the ethanol is evaporated and the residue is distilled in a high vacuum; B.P. 131°/0.07 mm. of Hg.

The distillate, which is a yellow, viscous oil and which consists of a mixture of cis and trans isomers (racemates) of the compound indicated in the heading, is chromatographed on 550 g. of neutral aluminium oxide. The cis isomer is eluted with benzene/ether (1:1); the dihydrochloride has a M.P. of 292-297° (decomp.) after crystallization from methanol. The trans isomer is eluted with ether/chloroform (1:1); the dihydrochloride has a M.P. of 307-309° (decomp.) after crystallization from ethanol.

(g) Cis-4-acetylaminio-1-methyl-3-(3,4-methylenedioxyphenyl)piperidine

2.8 g. of cis-1-methyl-3-(3,4-methylenedioxyphenyl)-4-piperidylamine (racemate) are dissolved in 10 cc. of chloroform and 1.9 g. of acetic anhydride are added while cooling with ice. The mixture is heated to the boil at reflux for 1 hour, is then cooled, diluted with chloroform and shaken out with 20 cc. of a saturated aqueous potassium carbonate solution. The chloroform layer is washed with a saturated aqueous sodium chloride solution, is dried over sodium sulphate and concentrated by evaporation. The compound indicated in the heading is obtained as

residue and is further worked up as crude product without previous purification.

EXAMPLE 4

2,6-dimethyl-8,9-methylenedioxy-1,2,3,4,4a,5,6,10b-octahydrobenzo[c][1,6]naphthyridine

1.6 g. of 2,6 - dimethyl-1,2,3,4,4a,10b-hexahydro-8,9-methylenedioxybenzo[c][1,6]naphthyridine dihydrochloride (racemate, production see Example 3) are dissolved in 500 cc. of 85% ethanol and hydrogenated in the presence of 100 mg. of a platinum catalyst at normal pressure and room temperature. After the theoretical amount of hydrogen has been taken up, the catalyst is filtered off and the filtrate is concentrated by evaporation. The 2,6-dimethyl - 8,9 - methylenedioxy - 1,2,3,4,4a,5,6,10b - octahydrobenzo[c][1,6]naphthyridine dihydrochloride (racemate) obtained as crystalline residue is recrystallized from 98% methanol; M.P. 294° (decomp.).

EXAMPLE 5

8,9-dimethoxy-1,2,3,4,4a,10b-hexahydro-2-methylbenzo[c][1,6]naphthyridine

43.0 g. of phosphorus oxychloride are added to a solution of 31.0 g. of cis-3-(3,4-dimethoxyphenyl)-4-formylamino-1-methylpiperidine (racemate as crude product) in 500 cc. of chloroform, and heating to the boil at reflux is effected for 1 hour, whereby the solution already becomes turbid and the formation of a crystalline precipitate commences. After cooling the reaction mixture the liquid is decanted, the residue is taken up in 100 cc. of water and the resulting clear solution is heated on a boiling water bath for 15 minutes. Cooling is again effected, solid potassium carbonate is added until an alkaline reaction is obtained and the oil which precipitates is extracted thrice with chloroform. The organic phases are combined, washed with a saturated aqueous sodium chloride solution, dried over sodium sulphate and concentrated by evaporation, whereby the compound indicated in the heading (as racemate) is obtained in the form of an oil which crystallizes; M.P. 108-110° after crystallization from ethyl acetate.

The starting material may, for example, be produced as follows:

27.0 g. of cis-3-(3,4-dimethoxyphenyl)-1-methyl-4-piperidylamine (racemate, production see Example 1) are heated to 130° together with 90 cc. of formamide in an atmosphere of nitrogen for 4 hours. The reaction mixture is subsequently cooled, diluted with water and extracted thrice with chloroform. Each of the chloroform layers is washed once with a saturated aqueous sodium chloride solution, the chloroform layers are combined, dried over sodium sulphate and concentrated by evaporation. The crude cis-3-(3,4-dimethoxyphenyl)-4-formylamino-1-methylpiperidine (racemate) obtained as a yellow, resinous residue, contains no impurities in accordance with thin layer chromatography and is further worked up without previous purification.

EXAMPLE 6

8,9-dimethoxy-2-methyl-1,2,3,4,4a,5,6,10b-octahydrobenzo[c][1,6]naphthyridine

15.7 g. of 8,9-dimethoxy-1,2,3,4,4a,10b-hexahydro-2-methylbenzo[c][1,6]naphthyridine (racemate, production see Example 5) are dissolved in 300 cc. of ethanol and hydrogenated in the presence of 300 mg. of pre-hydrogenated platinum oxide at room temperature and normal pressure, whereby the taking up of hydrogen stops after 3½ hours (1480 cc.=98% of the theoretical amount of hydrogen are taken up). The catalyst is filtered off, the filtrate is concentrated and the small amount of precipitate which results is filtered off; a solution of 15.0 g. of maleic acid in 30 cc. of methanol is subsequently added to the filtrate, the mixture is allowed to crystallize and the precipitate is isolated by filtration.

The resulting bis-(hydrogen maleate) of the compound indicated in the heading (racemate) is recrystallized from methanol/water; M.P. 190° (decomp.), sintering above 175°. The dihydrochloride has a M.P. of 343° (decomp.), dark colouration and sintering above 320° (crystallized from water).

EXAMPLE 7

8,9-dimethoxy-2-methyl-1,2,3,4,4a,5,6,10b-octahydrobenzo[c][1,6]naphthyridine

64.6 g. of cis-3-(3,4-dimethoxyphenyl)-1-methyl-4-piperidylamine dihydrochloride (racemate, production see Example 1) are dissolved in 200 cc. of water with heating, the solution is cooled and 20 cc. of 2 N hydrochloric acid and 35.0 g. of a 35% aqueous formaldehyde solution are added. The mixture is heated on a boiling water bath for 1 hour, whereby the formation of a colourless precipitate already commences after 5 minutes. Cooling is effected and the resulting 8,9-dimethoxy-2-methyl-1,2,3,4,4a,5,6,10b-octahydrobenzo[c][1,6]naphthyridine dihydrochloride is filtered off. M.P. 343° (decomp.), dark colouration and sintering above 320°; upon recrystallization from water the melting point is 25 no longer raised.

EXAMPLE 8

2-methyl-8,9-methylenedioxy-1,2,3,4,4a,5,6,10b-octahydrobenzo[c][1,6]naphthyridine

6.0 g. of cis-1-methyl-3-(3,4-methylenedioxyphenyl)-4-piperidylamine (racemate, production see Example 3) are dissolved in 35 cc. of 2 N hydrochloric acid and 5.0 g. of a 35% aqueous formaldehyde solution are added. The mixture is allowed to stand at room temperature for half an hour, is heated to 100° for half an hour and is subsequently evaporated to dryness. The hydrochloride of the compound indicated in the heading (racemate) obtained as residue is recrystallized from 40 methanol and has a M.P. of 304° (decomp.).

EXAMPLE 9

8,9-dimethoxy-2,6-dimethyl-1,2,3,4,4a,5,6,10b-octahydrobenzo[c][1,6]naphthyridine

15.0 g. of cis-3-(3,4-dimethoxyphenyl)-1-methyl-4-piperidylamine (racemate, production see Example 1) are heated to 100° with 7.5 g. of acetaldehyde for half an hour. 160 cc. of N hydrochloric acid are then added, the mixture is heated to 100° for a further 8 hours and the excess aldehyde and hydrochloric acid are subsequently evaporated in a vacuum. A saturated aqueous potassium carbonate solution is added to the residue and extraction is effected with chloroform; the chloroform layer is washed with a saturated aqueous sodium chloride solution, dried over sodium sulphate and concentrated by evaporation. The residue is chromatographed on 450 g. of neutral aluminum oxide. Elution with petroleum ether/ether (1:1) or ether/chloroform (1:1) yields a yellowish, viscous oil, which is taken up in ethanol. A solution of hydrogen chloride in ethanol is added until an acid reaction to Congo red is obtained, ether is added and the mixture is allowed to crystallize in a refrigerator. The precipitate is filtered off and crystallized several times from methanol/water, whereby the dihydrochloride of the compound indicated in the heading (racemate), having a M.P. of 328° (decomp.), is obtained. The free base has a M.P. of 122° after crystallization from ethyl acetate.

EXAMPLE 10

Galenic Preparation.—Tablets

		Grams
5	8,9 - dimethoxy-2,6-dimethyl-1,2,3,4,4a,5,6,10b-octahydrobenzo[c][1,6]naphthyridine dihydrochloride (compound of Example 2)	¹ 0.0260
10	Magnesium stearate	0.0010
	Polyvinyl pyrrolidone	0.0040
	Talcum	0.0080
15	Maize starch	0.010
	Lactose	0.1075
	Dimethyl silicone oil	0.0005
	Polyethylene glycol 6000	0.0030

15 For a tablet of 0.160

¹ Corresponds to 20 mg. of the free base.

What is claimed is:

1. A compound of formula:

30 in which:

R₁ is lower alkyl of 1 to 3 carbon atoms, R₂ is hydrogen or methyl,

each of the two symbols R₃ is lower alkoxy of 1 to 4 carbon atoms,

35 or together the two symbols R₃ are methylenedioxy, and each of the two symbols X is hydrogen, or together the two symbols are a second bond between the carbon and the nitrogen atom, and a pharmaceutically acceptable acid addition salt thereof.

2. 8,9-dimethoxy - 2,6 - dimethyl - 1,2,3,4,4a,10b-hexahydrobenzo[c][1,6]naphthyridine, in accordance with claim 1.

3. 8,9 - dimethoxy - 2,6 - dimethyl - 1,2,3,4,4a,5,6,10b-octahydrobenzo[c][1,6]naphthyridine, in accordance with claim 1.

4. 2,6 - dimethyl - 1,2,3,4,4a,10b - hexahydro-8,9-methylenedioxybenzo[c][1,6]naphthyridine, in accordance with claim 1.

50 5. 2,6-dimethyl - 8,9 - methylenedioxy - 1,2,3,4,4a,5,6,10b-octahydrobenzo[c][1,6]naphthyridine, in accordance with claim 1.

6. 8,9-dimethoxy - 1,2,3,4,4a,10b - hexahydro-2-methylbenzo[c][1,6]naphthyridine, in accordance with claim 1.

55 7. 8,9-dimethoxy - 2 - methyl - 1,2,3,4,4a,5,6,10b-octahydrobenzo[c][1,6]naphthyridine, in accordance with claim 1.

8. 2-methyl - 8,9 - methylenedioxy - 1,2,3,4,4a,5,6,10b-octahydrobenzo[c][1,6]naphthyridine, in accordance with claim 1.

UNITED STATES PATENT OFFICE
CERTIFICATE OF CORRECTION

Patent No. 3,503,981 Dated March 31, 1970

Inventor(s) Rudolf Suess et al

It is certified that error appears in the above-identified patent and that said Letters Patent are hereby corrected as shown below:

In the printed patent, column 8, line 53 change:

755 cc. to -- 750 cc.

Column 1⁴, claim 1, fourth line from bottom of claim 1:

After "symbols" insert -- X --.
